CLAIM

(21) Appl. No.: **29/240,965**

The ornamental design for an instrument for detecting which electrical plug is connected to a particular circuit breaker, as shown.

(22) Filed: **Oct. 21, 2005**

DESCRIPTION

(51) **LOC (8) Cl. 10-04**

FIG. 1 is a top, side and rear perspective view of an instrument for detecting which electrical plug is connected to a particular circuit breaker, showing my design;

(52) **U.S. Cl. D10/78**

FIG. 2 is a top plan view thereof;

(58) **Field of Classification Search** D10/78;

FIG. 3 is a side elevational view thereof, the side opposite that shown in FIG. 3 being the mirror image thereof; and, FIG. 4 is a bottom plan view thereof.
